UNITED STATES PATENT OFFICE.

JONES PINNELL, OF PITTSTON, PENNSYLVANIA.

IMPROVEMENT IN BELT-TIGHTENERS.

Specification forming part of Letters Patent No. 134,309, dated December 24, 1872.

To all whom it may concern:

Be it known that I, JONES PINNELL, of Pittston, in the county of Luzerne and State of Pennsylvania, have invented a certain Improvement in a Belt-Tightener for Sewing-Machines, of which the following is a specification:

This invention has for its object to improve the construction of belt-tighteners in such manner as to prevent the belt from slipping off the tightening-roller when the latter is pressed against the former. To this end the invention consists in the construction and arrangement of parts, which I will now proceed to explain.

Figure 1 is a perspective view, and Fig. 2 is a side elevation.

A is a plate, the same being supposed to be screwed to the under side of a sewing-machine. B is a bar, the same having a slot, a, through which a set-screw, c, passes into the plate A. The bar B has at one end two curved arms, e, which, in the position assumed for the apparatus, would extend downward from the under side of the table. Between these arms is

mounted a roller, i. The arms e project past the roller i, as shown, to a sufficient distance to form stops for the belt at each side, so as to prevent the belt from slipping off the roller. The belt m is supposed to pass between the arms e; hence, by moving the latter, the set-screw being loosened toward the belt, the latter can be tightened to any required degree, and by moving the bar away from the belt the latter is loosened.

I am aware that a roller in a sliding bar is not new as a belt-tightener.

I claim as my invention—

The combination of the flat plate A, slotted bar B, set-screw c, curved arms e, and roller i, said roller being placed between said arms, and the latter projecting past the roller so as to form stops for the belt at both sides, all constructed, arranged, and operating as and for the purpose described.

JONES PINNELL.
